WALTER J. GIRYOTAS, OF CHICAGO, ILLINOIS, ASSIGNOR TO ROBERT W. HUNT COMPANY,
OF CHICAGO, ILLINOIS, A CORPORATION OF DELAWARE

TESTING DEVICE

Application filed September 29, 1928. Serial No. 309,325.

This invention relates to the design and control of concrete mixtures and aims to provide improved means for effecting such design and control.

5 The invention may be readily understood from the following description of one procedure in which the apparatus illustrated in the drawings is employed in connection with determining certain properties of aggregate 55 for concrete.

In said drawings:

Fig. 1 is an elevation, partly in section, of a measuring device containing a quantity of aggregate.

15 Fig. 2 is a similar view of the same device containing a different percentage of aggregate.

Fig. 3 is a cross section taken along the line 3—3 of Fig. 1.

20 Concrete is a mixture of cement, water and inert materials known as aggregate, manipulated and handled in plastic condition, but hardening soon after upon hydration of the cement. Recent studies in the design of concrete mixtures has demonstrated that the character of the concrete depends upon the ratio of water used, upon the character of the aggregate, and of course upon the quantity of cement used. The following description 25 deals with determining the pertinent characteristics of the aggregate employed.

Aggregate is generally classified into fine and coarse materials, the fine usually consisting of sand and fine gravel and the coarse of 35 coarse gravel or crushed stone, etc. In order to determine the most economical proportions of cement and aggregate for producing concrete of the desired strength and other characteristics, it is necessary to know the fineness modulus of the aggregate. The fineness modulus of the aggregate depends upon the varying proportions of the different sizes of materials comprising the aggregate. Tests have shown that aggregates having the same 40 fineness modulus require equal amounts of mixing water for a given plasticity and consequently will produce concrete of the same strength, so long as other conditions are equal and the aggregate is not too coarse for the 45 quantity of cement used.

To determine the fineness modulus of aggregate according to the illustrative procedure and with the use of the apparatus shown in the drawings, the cylinder 10 which for the finer aggregate may conveniently be 55 about two inches in diameter and ten inches high, is filled to the top with a representative sample of the aggregate. It should be noted that in the event the aggregate contains very coarse material, a somewhat larger cylinder 60 may advantageously be employed. The actual volume of the cylinder is immaterial since the fineness modulus depends upon the relative percentages of different sizes of materials. The aggregate in the cylinder is 65 then graded and sized by a series of standard screens or sieves, one type of which is illustrated in my co-pending application filed concurrently herewith Serial No. 309,326. In order to standardize the sieves and sieve 70 sizes, the following sieves are employed in the determination: 1½ inch mesh, ¾ inch mesh, ⅜ inch mesh, No. 4, No. 8, No. 16, No. 30, No. 50, No. 100. The mesh of the last six sieves corresponds with its size number. 75 That is, No. 4 sieve has four mesh to the inch, No. 8 eight mesh to the inch and so on.

The measure of aggregate is first dumped upon the 1½ inch sieve and ordinarily none will remain on the sieve since in practice the aggregate does not contain material which will not pass through a 1½ inch mesh. It is thereupon placed upon the ¾ inch mesh sieve and the residue remaining on the sieve, that is the aggregate which will not pass through 85 the ¾ inch mesh, is returned to the cylinder 10. The percentage of this residue to the total is determined by the graduated measuring plunger 11 which in this instance is in the form of a closed cylinder of a diameter 90 just small enough to slide freely within the cylinder 10 and containing a scale 12 graduated in this instance into hundredths throughout a distance corresponding to the height of cylinder 10. The plunger is advantageously provided with a handle 13. The plunger is dropped upon the aforementioned residue, leveling it in the action and indicating on the scale (see Fig. 1) the proportion which this residue bears to the total. For 95 100

example, in Fig. 1 the scale, which is zero at the top, shows that the aggregate in the cylinder is slightly more than 10% of the total volume. The percentage of this residue is then recorded and the aggregate which passed through the $\frac{3}{4}$ inch screen is then placed on the $\frac{3}{8}$ inch mesh screen and a similar operation performed for the residue which remains on the $\frac{3}{8}$ inch screen. The percentage of this residue as determined by the measuring cylinder is recorded and the procedure followed through for No. 4 screen. Quite arbitrarily all material which will not pass through a No. 4 screen is regarded as coarse aggregate and all which is finer than a No. 4 screen is regarded as fine aggregate. The sum of the percentages of the respective residues retained on the $1\frac{1}{2}$ inch, $\frac{3}{4}$ inch, $\frac{3}{8}$ inch and No. 4 screen divided by one hundred, is the fineness modulus for the coarse aggregate. While it is apparent that the fineness modulus depends upon the screen sizes used, such screen sizes having been standardized for this purpose, the fineness modulus then becomes an index of the characteristics of the aggregate.

A similar procedure is followed through with the fine aggregates by the use of screen sizes Nos. 8, 16, 30, 50, and 100. The total of the percentages of the respective residues divided by one hundred representing the fineness modulus of the fine aggregate. The total of the two fineness moduli is the fineness modulus of the aggregate as a whole.

35 The fineness modulus thus determined, as stated above, is an index by means of which can be determined the proper volume of aggregate which should be used in a given concrete mixture.

40 In order to obtain mixed aggregate having a given fineness modulus, the respective moduli of the fine and coarse aggregate as above determined, may be utilized in an obvious manner to determine the necessary proportions of fine aggregate and coarse aggregate to the total aggregate.

45 Obviously the invention is not limited to the precise details of the illustrative embodiments thereof herein described, since such details may be variously modified. Moreover, it is not indispensable that all features be used conjointly since various features may be advantageously used in different combinations and sub-combinations.

50 Having described one embodiment of my invention, I claim:

55 A device for use in determining the fineness modulus of aggregate for concrete comprising in combination a cylindrical receptacle closed at its bottom and open to its full cross section at its top and of uniform cross section from its bottom to its top edge and adapted to be filled to its top edge, a cylindrical plunger as long as said receptacle and of a diameter just enough smaller than

that of the internal diameter of the cylinder to slide easily therein and being of uniform cross section from top to bottom, said plunger being removable to permit introduction of material into said receptacle and serving as a top closure for said receptacle, said plunger having a scale on the face graduated in hundredths through a distance corresponding to the height of the cylinder and arranged to indicate zero when the bottom of the plunger contacts with the bottom of the cylinder, whereby the reading on the scale coinciding with the top edge of said receptacle indicates the percentage of total cylinder volume represented by the space between the plunger bottom and cylinder bottom.

60 In testimony whereof, I have signed my name to this specification.
